& Brickmire,
Attorneys.

UNITED STATES PATENT OFFICE.

WOLFGANG BÄSELER, OF LICHTENCHAIN (SCHWARZBURG-RUDOLSTADT), GERMANY,
ASSIGNOR TO THE FIRM OF DEUTSCH-LUXEMBURGISCHE BERGWERKS-UND HÜT-
TEN-AKTIENGESELLSCHAFT OF DORTMUND, GERMANY.

DOUBLE COMPOUND OF RAILWAY LINES.

Application filed September 2, 1921. Serial No. 493,172.

(GRANTED UNDER THE PROVISIONS OF THE ACT OF MARCH 3, 1921, 41 STAT. L., 1313.)

To all whom it may concern:

Be it known that I, WOLFGANG BÄSELER, citizen of Germany, residing at Lichtenchain (Schwarzburg-Rudolstadt), Germany, 5 have invented certain new and useful Improvements in Double Compounds of Railway Lines (for which I have filed application in Germany, Jan. 4, 1918; Austria, Dec. 23, 1918; Switzerland, Dec. 27, 1918; 10 Sweden, Dec. 28, 1918; Hungary, Jan. 2, 1919; Denmark, Jan. 2, 1919; Holland, Jan. 4, 1919; Finland, Jan. 13, 1919; Norway, Jan. 21, 1919; Italy, Feb. 6, 1919; France, Feb. 21, 1919; Luxemburg, Feb. 26, 1919; 15 Belgium, Apr. 30, 1920; Great Britain, May 29, 1920; Czechoslovakia, July 7, 1920; Poland, July 8, 1920), of which the following is a specification.

This invention relates to double-slip 20 switches commonly used at railroad crossings.

In large railroad terminals having many tracks it is frequently desirable to provide switching facilities between tracks remote 25 from each other and even between the tracks at opposite sides, but a continuous switch track interconnecting all tracks is out of the question with switches usually employed, having a switch angle of approximately 1:9 30 because the length of such a switch track would be prohibitive in many cases.

Assuming for instance that it is desired at a terminal station to connect twenty tracks, spaced about 15 feet apart from center to center, by means of a switching track, this would require a length of 984 feet in the case of a switch angle 1:9, which length is ordinarily not available. A system, moreover, of the type referred to would be too 40 complex to be controlled by one shifting gang foreman only and would introduce difficulties of operation, delays and danger.

It is the object of this invention to provide a switch system including a single 45 switching track between remote tracks of an extended track system which is relatively short and simple in construction and operation.

For a full understanding of the invention reference is had to the accompanying drawings in which—

Fig. 1 is a plan view of a single track intersection;

Fig. 2 is a section on a larger scale of a tongue forming an important detail of the 55 invention; and

Fig. 3 is a transverse section on the line 3—3, Fig. 2.

Fig. 1 indicates diagrammatically two parallel tracks and a switch track for interconnecting the same. It is understood that the two parallel tracks are representative of any plurality of parallel tracks, the relation between the switching track and each of the parallel tracks being identical.

In the drawings *a b c d* designate the so called "crossing square" by which is meant the quadrangle or diamond defined by the intersections of the rails of two tracks.

While in ordinary constructions of this 70 type the switch curves or slips lie entirely within the "crossing square," it is a characteristic feature of this invention that parts of the switching curves extend beyond and lie outside the "crossing square."

Another characteristic feature is a single double-tread rail *e* extending diagonally across the "crossing square."

In the arrangement illustrated the ends *f* of the slip rails extend materially beyond 80 the points *a* and *c* of the crossing quadrangle. The curved stock rail portions *l* and *k*, as can be readily seen, curve away from the straight line of the respective tracks a substantial distance outwardly from 85 the line which passes through the points *a* and *c* respectively parallel to the ties. The curved portions *l* and *k* are thus moved away from the intersection points *d* and *b* respectively as compared with the practice 90 according to the prior art, and the parts of the portions *l* and *k* which are co-extensive with the length of the crossing quadrangle *a b c d* have such a large radius of curvature 95 that they approach straight lines. This disposition of the curved portions *l* and *k* leads

to the use of a single rail *e* forming the diagonal of the crossing quadrangle. The rail *e* is in fact a combination of two rails forming the mates of the curved portions *l* 5 and *h* respectively. The tread portion of the rail *e* facing the portion *l* is parallel thereto and the tread portion facing the portion *h* is parallel to the latter. The ends *f* form continuations of the rail *e* and 10 extending to the points at which the portions *l* and *h* curve away from straight lines serve their usual purpose of controlling the direction of travel.

The single rail *e* and the portions *f* are 15 inter-connected by a single solid block containing the usual tongue tip *i* and two additional tongues *g*, *h*, shown in detail in Figs. 3 and 4.

The ends *f* may be shifted in the usual 20 way.

By the arrangement proposed the crossing angle can be made larger and the inconveniences of the usual acute angle can thereby be overcome. The switching track can be 25 correspondingly shortened without decreasing the radius of curvature below the permissible minimum. The resulting advantages of the application of the principles described to a whole switching system at a 30 large terminal station are obvious.

In the foregoing the invention has been described merely by way of example and it is understood that the arrangement forming the invention is susceptible of various 35 changes and modifications in accordance with varying conditions to be met.

I claim:

1. In a railroad crossing switch the combination with two tracks crossing each other 40 and outer curved rails, each forming part of the two tracks, of a common center rail co-operating with both curved rails to define switching tracks and movable switch sections extending from each end of the common rail and forming continuations thereof.

2. In a railroad crossing switch, the combination with two tracks crossing each other defining thereby a crossing quadrangle, and

outer curved rails, each forming part of the two tracks, of a common center rail and 50 movable switch sections extending from opposite ends thereof, the common center rail and one section at each end thereof co-operating with one curved rail, and the common rail and another section at each end thereof, co-operating with the other curved rail.

3. In a railroad crossing switch, the combination with two tracks crossing each other defining thereby a crossing quadrangle, and outer curved rails forming part of the two tracks, of means co-operating with the said curved rails for providing switching tracks, 60 said means including movable switch sections extending outwardly from each of opposite corners of the quadrangle and a common rail having a tread portion on each side, one tread in conjunction with one of said switch sections at each end co-operating with one of said curved rails and the other tread in conjunction with the other switch section at each end co-operating with the other curved rail.

4. In a railroad crossing switch, the combination with two tracks crossing each other defining thereby a crossing quadrangle and outer curved rails forming a part of each track, of means co-operating with the said curved rails for providing switching tracks, 65 said means including movable switch sections extending outwardly from opposite corners of the quadrangle.

5. In a railroad crossing switch, the combination with two tracks crossing each other and thereby defining a crossing quadrangle 85 and outer curved rails forming a part of each track, of solid blocks in the acute angled corners of the quadrangle embodying each three tongue tips, and movable switch sections 90 extending outwardly from each block for co-operation with the two tracks respectively.

In testimony whereof, I affix my signature.

WOLFGANG BÄSELER.
